US00D892084S

(12) **United States Design Patent** (10) Patent No.: **US D892,084 S**
(45) Date of Patent: ** Aug. 4, 2020

(54) **REMOTE CONTROL**

(71) Applicant: **NVIDIA Corporation**, San Jose, CA (US)

(72) Inventors: **Kyu Sik Uhm**, Sunnyvale, CA (US); **Boris Landwehr**, Thousand Oaks, CA (US); **Andrew Robert Bell**, San Francisco, CA (US); **Pei-Lin Lo**, Taipei (TW)

(73) Assignee: **NVIDIA Corporation**, Santa Clara, CA (US)

(**) Term: **15 Years**

(21) Appl. No.: **29/693,093**

(22) Filed: **May 30, 2019**

(51) LOC (12) Cl. **14-03**

(52) U.S. Cl.

USPC **D14/218**

(57) **CLAIM**

The ornamental design for a remote control, as shown and described.

DESCRIPTION

FIG. 1 is a front view of the remote control showing the design;

FIG. 2 is a back view thereof;

FIG. 3 is a left side view thereof;

FIG. 4 is a right side view thereof;

FIG. 5 is a top view thereof;

FIG. 6 is a bottom view thereof;

FIG. 7 is perspective view of the front; and,

FIG. 8 is perspective view of the back.

The broken lines in the figures depict portions of the remote control that form no part of the claimed design.
